Attorneys

UNITED STATES PATENT OFFICE.

HAROLD PENDER, OF PHILADELPHIA, PENNSYLVANIA.

ENGINE-STARTING APPARATUS.

Application filed January 22, 1920. Serial No. 353,328.

This invention relates to the starting of internal combustion engines. One object is to provide simple and practical means for starting an engine of the above type. Another object is to provide means of the above type of efficient and dependable action. Other objects are to provide means of the above type which shall be automatic and adapted effectively to meet various contingencies arising in use. Other objects will be in part obvious and in part pointed out hereinafter.

The invention accordingly consists in the features of construction, combinations of elements, and arrangement of parts, all as will be illustratively herein described and the scope of the application of which will be indicated in the following claims.

In the accompanying drawing in which is shown one of various possible embodiments of the several features of this invention,

Figure 1 is a sectional plan taken along the line 1—1 of Figure 2;

Figure 2 is an end view of the apparatus mounted in condition for use; and

Figure 3 is a diagrammatic view of electrical connections.

Similar reference characters refer to similar parts throughout the several views of the drawing.

Referring now to Figure 2 of the drawing, there is shown at 10 a portion of an internal combustion engine, preferably the flywheel, provided with a gear 11 which may be if desired formed directly in the flywheel.

At 12 is shown a supporting member which preferably forms a portion of a casing extending about the flywheel and engine and enclosing the lower portion of the engine. In this casing an opening 13 is formed into which fits an annular projection or pilot 14 formed on the head of an electric starting motor 15. The motor is supported in any desired manner as by means of fitting its end within the flanged annular ring 16 as shown in Figure 1 of the drawing.

The armature shaft 17 of motor 15 is provided with a pinion 18 fast thereon and of course driven whenever the motor is in action.

At this point reference is made to Figure 3 in which the motor 15 is provided with electrical connections 19 for connecting it with a battery 20 which may be a storage battery mounted on the motor vehicle. The connection is made as by the swinging

switch member 21 shown in full lines in open-circuiting position and adapted to swing about its pivot into the position shown in dotted lines and thereby connect the motor with the battery. A spring 22 is connected between the switch arm and a point on the remote side of the switch pivot in such manner that it tends to hold the switch in either open or closed position alternatively and thus insures a full contact when thrown into its closing position, and an abrupt starting of the motor.

Recurring to the mechanism shown in Figures 1 and 2 of the drawing, there is interposed between the gear 11 and pinion 18 a floating pinion 23. This pinion is provided with a short shaft to extend to each side of the pinion and form the trunnions 24. These trunnions respectively rest within similar slots in a fitting 25 secured to the head of the motor as by a number of screws 26. Fitting 25 is provided with a pair of spaced bearing plates 27 and 28, the entire fitting being preferably cast integral and the plate 28 held in position as by the arms 29 provided with suitable stiffening ribs 30. The pinion 23 normally rests with its trunnions in the lower ends of the slots in which these trunnions have a circular bearing engagement as at 31. It is normally held by gravity in this position and it is to be understood that the preferred disposition of this apparatus is at the lower sector of the flywheel on the side of the wheel which descends in the regular order of rotation of the engine. The order of rotation of the several gears is indicated by the arrows. The pinion in this position is out of engagement with the gear 11 and is in engagement with the pinion 18 but preferably out of pitch line relation; that is, only partially inter-meshed. The slots in which these trunnions are mounted permit the pinion to rise so that its trunnions engage upper bearing surfaces 32, identical in each slot and rounded to fit the trunnion surface 100 and form a low friction bearing. In this position the pinion 23 is in exact pitch line meshed relation to both pinion 18 and gear 11. The lower position of the pinion however shown in Figure 2 of the drawing, is its normal inactive position and it may be held there by gravity notwithstanding jarring. There are provided, however, for use, if desired, a pair of light springs 33 identical on both sides of the pinion and slightly over-

lapping the trunnions to render more secure the pinion remaining in its lowermost position. They offer, however, when the parts are actuated, a negligible resistance to a rising movement of the pinion.

There is also shown for use if desired a heavier spring 34 which may be duplicated on both sides of the pinion and which curves over the trunnion as at 35 to be engaged by 10 the trunnion before it engages the bearing surface 32 and slightly cushion any tendency to shock of the parts. A spring having this action however, is not essential to the broad principles of my invention although under 15 certain conditions it may be advantageous.

In brief resumé of the condition of the parts as they stand inactive, the pinion 23 rests with its trunnions in the bearing surface 31 with substantially no resistance to 20 upward movement and it is preferably so shaped including its trunnions as to be symmetrical with respect to its central transverse plane.

With the parts thus positioned, it is desired to start the engine, and assuming that 25 the gear 11 is at rest, the circuit is closed from battery 20 to motor 15 by swinging over the switch the arm 21 which instantly completes a connection with the battery.

30 The motor is immediately started under high speed and the engagement of its pinion with the teeth of pinion 23 instantly exerts a lifting force on the latter. The latter, it is to be noted, although free to rotate and pref-

35 erably having a bearing with the friction reduced to a minimum, does not instantly rotate on account of its rotary inertia. This feature is important and the action of the apparatus will in many respects be enhanced

40 by the rotary inertia of the pinion 23 as by suitable shaping of its cross-section to bring its weight away from its axis. By this or other means it is given a high moment of inertia relative to its weight and, in the construction shown, a considerably greater moment of inertia relative to its weight than that of the pinion 18. Before the pinion 23 can, due to its inertia, rotate at a substantial speed, it has been given a strong lifting

45 impulse from the pinion 18 which is ample to raise it into mesh with the teeth of gear 11 and upon further rotary tendency of the pinion 18, to bring it solidly against its bearing surface 32. In other words, when a sud-

50 den force is applied to a body, the resultant of which force is eccentric with respect to the center of gravity of the body, the latter has a tendency to movement which may be considered as comprising two components, 55 first a motion of transition, and second a motion of rotation about its center of gravity. In this case the transitory component is utilized to give the pinion a bodily movement and its slight rotary tendency facilitates its rolling into mesh with the gear 11.

The engagement with gear 11 is cushioned by the springs 34 if the latter be used, although the action by which the pinion 23 is rolled into mesh with the gear 11 is in a way gradual, and tends to reduce shock to a minimum.

It may be noted at this point that by the expression "outwardly" is meant the direction away from the axis of the member with respect to which it is used, and also that the term "gear" is used in a broad sense to comprehend not merely an element with a single set of gear teeth but an element of this nature in which more than one set may be provided.

It is to be understood that during the normal actuation of the parts as above described, the trunnions 24 ride upwardly in their slots along the sides remote from the pinion 18 due partially to the outward thrust caused by the teeth of the latter. If however the teeth of the pinion 23 meet the teeth of the gear 11 at precisely such angular relation as would prevent them from rolling into mesh, the trunnions are forced away from the straight surfaces 36 of the slots toward the opposite walls 37. The latter are recessed so as to permit a lateral movement of the trunnions within the slot at intermediate points, and in case of the above tendency to jam, the pinion merely rides out of its normal upward course to a slight extent away from the flywheel gear, thus relieving this jamming tendency and rolling the teeth properly into mesh.

When the pinion as pinion 23 has reached its upward limit, the bodily movement is stopped and it immediately is driven in ordinary rotation by the pinion 18, thus rotating the flywheel 10 and cranking the engine. 105 When the engine fires, there is a reverse pressure upon the adjacent teeth of the pinion 23 which in co-action with gravity and with the springs 34, if the latter be used, immediately throws the pinion to its lowermost position. It is to be understood that generally speaking the rate of peripheral travel of the gear 11 will be greater than that of the gear 18 and hence there is a positive downward thrust on the pinion 23 even apart from its reluctance, due to its inertia, instantly to partake of a higher speed of rotation. 110

When the pinion 23 has been thus demeshed, even though the electric motor be maintained running at full speed, there will be no tendency to re-mesh the gears as pinion 23 is already running at full speed and hence its rotary inertia is not effective in causing it to lift again into mesh with the flywheel gear. This is of great value as compared with an arrangement in which friction is depended upon to throw the gearing into mesh. The friction would remain effective and tend to cause the re-meshing of a moving flywheel gear. Furthermore, even 120

though the motor 15 with its pinion and pinion 23 be brought to rest after the engine be started, and if then for any reason the electric motor is again started although it will 5 tend to lift pinion 23 against the rotating flywheel gear, nevertheless as inertia only is depended upon, the merest contact with the moving flywheel gear will apply a rotary force to the pinion not only from the part 10 18 but from the flywheel, and instantly negative the lifting tendency. This contact, moreover, with the moving gear is not only slight but is evenly applied along the whole length of the contacting tooth and thus does 15 no injury to either of the parts.

By the above method of control and actuation of parts, certain features are utilized which may be advantageously used by apparatus which differs marked from that 20 herein described.

The apparatus hereinbefore described is readily assembled and taken apart with reference to the engine and is securely held in the desired position without necessity for 25 adjustment. The electric motor with the parts mounted thereon may be of standard shape and form and if the opening 13 be properly positioned in the engine casing or like part, and the screws by which the motor 30 is secured within the flange 16 register with properly placed holes in the motor shell, then whenever the motor is simply slipped in place and the screws driven home, all parts are in the exact predetermined relation 35 for best action. The motor with its gearing mounted thereon may be hooked into the opening 13 by a proper spacing as at 38 and thus these parts may be assembled as a unit for being inserted into the engine 40 casing, and the flange member 16 may then be secured to the engine casing and to the motor.

It will thus be seen that there is provided apparatus in which the several objects of 45 this invention are achieved and that it is well adapted to meet the conditions of the hardest practical use.

As various possible embodiments might be made of the features of this invention, it is to be understood that all matter herein set forth or shown in the accompanying drawing is to be interpreted as illustrative and not in a limiting sense.

I claim as my invention:

55 1. In engine starting apparatus, in combination, an engine driven gear, an auxiliary starting motor, a gear driven from said starting motor, a third gear, and means mounting said third gear in a position normally in engagement with said second gear and out of engagement with said first gear and laterally offset therefrom and shaped to permit bodily movement of said third gear and guide it laterally into mesh with 60 said first gear in a path non-concentric with

respect to the axis of said second gear upon said motor being driven in a predetermined direction.

2. In engine starting apparatus, in combination, an engine driven gear, an auxiliary 70 starting motor, a gear driven from said starting motor, an intermediate gear, and means mounting said intermediate gear in a position outwardly offset from said first gear and partially intermeshing with said 75 second gear and adapted to guide it upon said motor being driven in a predetermined direction into full mesh with both said first and second gears.

3. In engine starting apparatus, in combination, an engine driven gear, an auxiliary starting motor, a gear driven from said starting motor, an intermediate gear normally positioned with its axis at a distance from the axis of said second gear greater 80 than the sum of the pitch-line radii of said gears and less than the sum of the extreme radii of said gears whereby their teeth are partially meshed in a radial direction, and means mounting said third gear to guide it 85 into full mesh with said first and second gears upon said motor being started in a predetermined direction.

4. In engine starting apparatus, in combination, an engine driven gear, an auxiliary 90 starting motor, a gear driven from said starting motor, a third gear outwardly offset from said first gear and having a large moment of inertia relative to its weight, and means mounting said third gear in a position in which it is normally in engagement with said second gear and out of engagement with said first gear and shaped to permit its movement from such normal position to a position in which it is in mesh with 95 said first and second gears upon said motor being driven in a predetermined direction.

5. In engine starting apparatus, in combination, an engine driven gear, an auxiliary starting motor, a gear driven from said 100 starting motor, a third gear outwardly offset from said first gear and normally out of mesh with the same and in engagement with said second gear, means mounting said third gear to permit it to be moved automatically 105 by the starting of said motor into a position in which it is in mesh with both said first and second gears, and a yieldable member tending to hold said third gear in its normal position and positioned to become substantially inoperative after the first portion of the movement of said gear.

6. In engine starting apparatus, in combination, an engine driven gear, an auxiliary starting motor, a gear driven from said 110 starting motor, a third gear having an axial member, and a mounting for said third gear provided with slots in which said axial member rests, said slots being formed to mount said third gear in engagement with 115 120 125 130

4
said second gear and out of engagement with said first gear when said axial member is adjacent one end thereof, and to mount said third gear in a position in which it is in mesh with both said first and second gears when said axial member is in a position adjacent the opposite ends of said slots.

5 7. In engine starting apparatus, in combination, an engine driven gear, an auxiliary starting motor, a gear driven from said starting motor, a third gear having an axial member, and a mounting for said third gear provided with slots in which said axial member rests, said slots being formed to 10 mount said third gear in engagement with said second gear and out of engagement with said first gear when said axial member is adjacent one end thereof, and to mount said third gear in a position in which it is in mesh with both said first and second gears when said axial member is in a position adjacent the opposite ends of said slots, said mounting being secured to the head of said motor.

15 8. In engine starting apparatus, in combination, an engine driven gear, an auxiliary starting motor, a gear driven from said starting motor, a third gear outwardly offset from said first gear and adapted to be 20 thrown by said second gear laterally into a position in which it meshes with both said first and second gears, and means adapted to co-act with said gear and so formed that in the event of the teeth of said third gear 25 tending to jam against the teeth of said first gear it will provide to said third gear a path for a jam-relieving movement whereby it rolls into mesh with said first gear.

30 9. In engine starting apparatus, in combination, an engine driven gear, an auxiliary starting motor, a gear driven from said starting motor, a third gear outwardly offset from said first gear and normally out of mesh therewith and in engagement with said 35 second gear, and means mounting said third gear to permit it to move in a predetermined path laterally into mesh with said first gear and to move into mesh along another path upon its teeth tending to jam 40 against those of said first gear.

45 10. In engine starting apparatus, in combination, an engine driven gear, an auxiliary starting motor, a gear driven from said starting motor, a third gear outwardly offset from said first gear and normally out of mesh therewith and in engagement with said second gear, said gear being provided with a projecting part, and mounting means for said third gear comprising a slot within 50 which said part upon said third gear rests and along which it may move into a position in which it is in mesh with both said first and second gears, said slot being wider than the member resting therein.

55 11. In engine starting apparatus, in com-

bination, an engine driven gear, an auxiliary starting motor, a gear driven from said starting motor, a third gear outwardly offset from said first gear and normally out of mesh therewith and in engagement with said second gear, said gear being provided with a projecting part, and mounting means for said third gear comprising a slot within which said part upon said third gear rests and along which it may move into a position in which it is in mesh with both said first and second gears, said slot being rounded at each end to form a bearing for said third gear and being broadened intermediate its ends to permit sidewise movement of said third gear with respect thereto.

60 12. In engine starting apparatus, in combination, an engine driven gear, an auxiliary starting motor, a gear driven from said starting motor, a third gear normally in connection with said second gear and outwardly offset from and out of mesh with said first gear, an axial member extending through said third gear, and means mounting said axial member to permit either end thereof to be moved independently, said third gear with its axial member being symmetrically formed with respect to its central transverse plane whereby it is evenly moved by said second gear toward meshing position with said first gear upon said motor being started in a predetermined direction.

65 13. In engine starting apparatus, in combination, an engine driven gear, an auxiliary starting motor, a gear driven from said starting motor, a third gear outwardly offset from said first gear and normally out of mesh therewith and in engagement with said second gear, means mounting said third gear whereby upon said motor being started 100 said third gear is moved bodily because of its inertia and consequent resistance against starting to rotate and is thrown into mesh with said first gear, and means adapted to cushion the stoppage of the meshing movement of said third gear, said last means being substantially out of operative relation to said third gear during the first portion of the movement thereof.

70 14. In engine starting apparatus, in combination, an engine driven gear, an auxiliary starting motor, a gear normally outwardly spaced from said engine gear, and means actuated from said motor adapted upon said motor being started to rotate said gear, and means adapted to utilize the inertia of said gear and its consequent resistance to starting to rotate in rolling it into mesh with said engine gear, said means being shaped to permit said gear to deviate from its normal path of movement upon tending to jam against the teeth of said engine gear.

75 15. An automatic drive for starting a heat engine including in combination a starting pinion, a gear of a heat engine rotatable 120

thereby, a floating gear for transmitting rotational movement from the pinion to the first mentioned gear, and a supporting member upon which said floating gear is slidably mounted, said member being so arranged that said starting pinion will cause said floating gear to slide thereon laterally and radially into engagement with the heat engine gear for starting said heat engine, and so arranged that said heat engine gear when started will automatically disengage said floating gear and cause it to slide back on said member out of engagement therewith.

16. An automatic drive including in combination a starting pinion, a gear of a heat engine rotatable thereby, a floating gear for transmitting rotational movement from the pinion to the first mentioned gear, a supporting member for slidably supporting said floating gear and mounted adjacent said pinion and said first mentioned gear, whereby said starting pinion will cause said floating gear to slide laterally and radially into mesh with said heat engine gear, and yielding means mounted on said member for limiting the movement of said gear thereon.

17. An automatic drive including in combination a starting pinion, a gear of a heat engine rotatable thereby, a floating gear for transmitting rotational movement from the pinion to the first mentioned gear, and means for carrying said floating gear whereby it will loosely engage said pinion whereby it will be free to disengage itself from facing the teeth of said first mentioned gear.

18. In automatic starting apparatus for an internal combustion engine, in combination, a motor-driven rotary driving member, a rotary power-transmitting member on the engine, an intermediate rotary power-transmitting member normally out of engagement with said engine member, and means mounting said intermediate member to adapt it

to move about a variable radius with respect to the axis of said first rotary member into power-transmitting relation between said rotary means upon the motor being started.

19. In automatic starting apparatus for an internal combustion engine, in combination, a motor-driven rotary driving member, a rotary power-transmitting member on the engine, an intermediate rotary power-transmitting member normally out of engagement with said engine member, and means mounting said intermediate member to adapt it to move about a variable radius with respect to the axis of said first rotary member into power-transmitting relation between said rotary means upon the motor being started, said last means comprising a pair of supporting members respectively on opposite sides of said intermediate member.

20. In automatic starting apparatus for an internal combustion engine, in combination, a motor-driven rotary driving member, a rotary power-transmitting member on the engine, an intermediate rotary power-transmitting member normally free from said engine member, and supporting means comprising a pair of members respectively on opposite sides of said intermediate member adapted to guide said intermediate member into power-transmitting relation by said first and second rotary members, each of said several rotary members being provided on its outer surface with projecting parts adapted to intermesh with the others, and said intermediate member having a connection with said supporting members adapted to permit relative rotary and bodily movement thereof.

In testimony whereof, I have signed my name to this specification this 9th day of January, 1920.

HAROLD PENDER.
